SAFETY PILOT BURNER

Hubert T. Sparrow, Minneapolis, Minn., assignor
to Minneapolis-Honeywell Regulator Company,
Minneapolis, Minn., a corporation of Delaware

Application June 15, 1940, Serial No. 349,745

8 Claims. (Cl. 136—4)

The present invention is concerned with pilot burners and more particularly those of the type which have associated therewith a thermally temperature responsive member adapted to control the operation of a control device.

It is quite conventional in the fuel fluid burning art, particularly where the fuel is gas, to provide a pilot burner construction which incorporates some temperature responsive means for indicating whether the pilot is burning or not. Due to the recent development of high permeability materials, it has become possible to use a thermocouple as a temperature responsive element in such an arrangement and due to the many advantages of the thermocouple in this connection, thermocouple safety pilots have been widely used in recent years. It is broadly an object of this invention to provide a safety pilot of this type which is extremely compact, in which the burner flame is effectively utilized both as an igniting flame and also to heat the thermocouple or thermocouples, and in which the thermocouple is of a type which furnishes a relatively large amount of power.

The object of the invention is accomplished by providing an extremely flat burner and a flat temperature responsive element which is subjected to a relatively long burner flame. The temperature responsive element is in the form of a flat thermocouple formed of one or more pairs of strips of material of different thermoelectric characteristics, the lateral edges of which strips are joined together adjacent their ends. By projecting the flame from an inclined burner face, a single flame is able to serve both as an igniting flame and also as a means for heating the thermocouple. The burner opening consists of a slit through a removable closure member so that the size of the burner opening can be readily adjusted by the selection of a closure member having a suitable slit. The burner head is provided with slots in its side which serve the dual function of providing mounting flanges and also of facilitating the introduction of the primary air into the burner. The burner construction further provides an ingenious method of mounting the thermocouples which utilizes a lug over which the thermocouple members are placed and which lug also may serve as a means for mounting the burner.

Other features and objects of the invention will be apparent from a description of the accompanying specification, claims and drawing of which

Figure 1 is a perspective view of one form of the improved burner construction.

Figure 2 is a vertical sectional view of the burner construction of Figure 1.

Figure 3 is an end elevational view of a modified form of the burner construction.

Figure 4 is an exploded view of the thermopile utilized in the construction of Figure 3.

Figure 5 is a view of a burner control system employing the improved burner construction as a pilot burner and showing one method of mounting the pilot burner, and

Figure 6 is a view of a main burner and the improved burner mounted in a somewhat different manner than in Figure 5.

Referring to the drawing, the burner head is generally indicated by the reference numeral 10 and the thermocouple member by the reference numeral 11. It will be noted that the burner head 10 consists of a block of rectangular cross section having an inclined forward face 14. At the lower end of burner head 10 is a cylindrical recess 15 and communicating with this recess is a passage 16. The passage 16 connects with a groove 17 extending transversely to the burner, this groove 17 being in the inclined face 14. The groove 17 extends over the greater length of the face 14 terminating just short of the ends thereof. A groove 18 is cut in the right hand face of the block 10 so as to provide a flange 20. A closure plate 22 which may be formed of sheet metal is secured over the inclined face 14 by means of curved portions 23 and 24 which extend over the uppermost edge of the burner head 10 and over the flange 20. The closure plate 22 is provided with a slit 25 therethrough which is of substantially the same length as the groove 17. This slit 25, as will be apparent from the later description, serves as a burner opening.

The lower end of the recess 15 is threaded so as to facilitate the securing therein of a jet member 21. This jet member has an intermediate hexagonal portion 26 for the application of a wrench thereto and the lower and upper threaded nipples 29 and 30. The lower nipple 29 is employed for connection with a fuel supply conduit. The upper nipple portion 30 cooperates with the threaded portion of recess 15 to secure the jet member 21 in position. The upper nipple 30 is provided with a relatively long extension 31 with a relatively small fuel passage extending therethrough.

Each of the side walls 34, only one of which appears in the drawing, is provided with a slot 35. The slot 35 performs two functions. In the first place, it provides a flanged portion 36 which serve as a means for mounting the burner head. The flange 36 is provided with an open-

ing 37 to accommodate a bolt, cap screw, or other similar fastening member. The slot is of sufficient depth so that there is only a thin wall between the bottom of the slot and recess 15. An aperture 38 extends through this wall so as to provide a passage for primary air to the interior of the recess 15. By reason of the slot 38, the air needs to pass only through a relatively thin wall in going into the recess 15.

The gas in passing through the relatively small final passage of jet member 27 issues from the jet member with considerable velocity and draws with it air through the openings 38. In passing through passage 16, the air and gas are thoroughly intermixed so as to form the desired combustible mixture. The gas mixture when it reaches the groove 17 is forced to spread out along the groove by reason of the relatively small size of the slit 25. The result is that the gas issues along the slit 25 to produce a relatively long burner flame. By reason of the inclination of the wall 23 and the corresponding inclination of the closure plate 22, the burner flame is inclined towards the right as indicated in Figure 2.

By providing a separate closure plate 14 and by making this removable, several advantages are obtained. In the first place, the machining operation is greatly simplified, as will be readily apparent. Furthermore, if the burner becomes clogged at any time due to the accumulation of gummy materials contained in certain types of gas, the closure plate 14 can be readily removed by sliding the same endwise. This exposes the channel 17 and facilitates the cleaning of the interior burner. Moreover, it is often desirable to have different sized burner openings with different types of fuel. It will be apparent that this can be readily accomplished with a burner construction of the present invention by providing closure plates having slits of different cross sectional area.

The portion of the device which has been described so far is solely that portion which functions as the burner. The design of the burner, however, is such as to facilitate efficient operation with a temperature responsive element, particularly with a thermocouple member. The thermocouple member 11 which is employed in the construction of Figures 1 and 2 is substantially of the type disclosed in Patent No. 2,278,744 issued April 7, 1942, to Hubert T. Sparrow and John M. Wilson. This thermopile comprises a plurality of strips 39, 40, 41, and 42. Strips 39 and 41 are of one material and strips 40 and 42 of another material having thermoelectric properties which are quite dissimilar than those of strips 39 and 41. Thus strips 39 and 41 may, for example, be formed of Constantan, an alloy composed of approximately 50% copper and 50% nickel and strips 40 and 42 may be formed of stainless steel. It will be understood that in place of Constantan and stainless steel any two other metals having proper thermoelectric characteristics may be employed. As indicated in the copending Sparrow and Wilson application referred to above, the individual strips may be secured together by rolling whereupon slots 44, 45, and 46 can be cut out to cause the elements to be separated except at the opposite ends. The result is that the elements are secured together so as to form two series connected thermocouples, the hot junctions of which are constituted by the functions at the upper ends between strips 39 and 40 and between strips 41 and 42. The lower

ends of strips 39 and 42 are turned outwardly to provide terminal ears 48 and 49. The right hand surface of the burner head is provided with a projecting portion 51. Extending to the right from this portion is a stud 52 which is of rectangular cross section. The stud is threaded on the upper and lower edges. The thermopile 11 is disposed over the stud 52 having an aperture therethrough which conforms in configuration to the cross section of the stud 52. This aperture is not shown in connection with the species of Figures 1 and 2 but is shown in Figure 4 in connection with the modified form. In this figure the aperture in question is designated by the reference numeral 53 and it is to be understood that an aperture similar to aperture 53 in size and location is provided in the thermopile unit 11. Strips 55 and 56 of heat resistance insulating material such as mica or asbestos are interposed on each side of the thermopile 11 to prevent short circuiting of the various component strips. The rigid sheet metal plate 58 is placed over the strips 56. This plate 58 as indicated in Figure 1 is grooved at 59 and 60 to provide ribs on its inner surface. These ribs are so located as to force the insulating sheet 58 in between the component strips of the thermopile. This serves not only to more effectively insulate these strips from each other but also to more securely position the thermopile. A nut 62 is threaded onto the stud 52 and serves to clamp the entire assembly including insulating strips 55 and 56, thermocouple unit 11 and plate 58 together against the burner head 10. By reason of the ribs provided by grooves 59 and 60 and by reason of the non-circular aperture 53 which closely conforms with the non-circular cross section of stud 52, the thermopile 11 is free from any tendency to turn about the stud 52. In this manner the single nut 62 is effective to hold the thermopile 11 rigidly in position. The hot junctions of the thermopile, it will be noted, are in the path of the flame issuing from the slit 25. The flame issuing from slit 25 is thus able to thoroughly heat the hot junctions and at the same time be available for its normal igniting function. As will be more clearly brought out later the diagonal path followed by the flame enables the burner to be mounted in either horizontal or vertical position with the assurance that in either case, the hot junctions of the thermocouple will be adequately heated by the burner flame.

The right hand end of the stud 52 is provided with an aperture 63 which is designed to receive a fastening member such as a bolt or screw. The stud 52 thus not only serves as a means for securing the thermopile in position but also may serve as a mounting means for the burner unit.

Species of Figures 3 and 4

The species of Figures 3 and 4 is identical to that of Figures 1 and 2 as far as the burner construction is concerned. For this reason, the burner construction will not again be described in detail and the reference numerals applied thereto are the same as used in connection with Figures 1 and 2. The only difference between the species of Figures 3 and 4 and that of Figures 1 and 2 is in the thermopile unit. It will be noted, particularly from Figure 4, that the thermopile generally designated as 11 comprises three units 72, 73, and 74. Each of these units is substantially the same as the thermopile 11 described in connection with Figures 1 and 2. Thus

each thermopile comprises two pairs of strips of dissimilar metals, these strips being connected together in series. The only difference between the units 72, 73, and 74 and the unit 11 is that the terminal lugs 18 and 19 corresponding to terminal lugs 48 and 49 are from necessity on different units. Thus terminal lug 18 is on unit 72 and terminal lug 19 on the unit 74. Each of the units is provided with an aperture 89 which corresponds in configuration to the cross section of the lug 52. The units 72, 73, and 74 are assembled together on the lug 52 with insulating strips 80, 81, 82, and 83 to separate them from the burner head and from each other at desired points. The insulating strips 80 and 83 are of the same area as the clamping plate 88 corresponding to clamping plate 58. In other words, these two insulating strips cover the entire possible area of contact between units 72 and burner head 10 and between units 74 and clamping plate 84. The insulating strips 81 and 82 are however provided with cut away portions to permit connection of the various units together. Thus referring to Figure 4, the insulating strip 81 is provided with a rectangular cut away portion 86 while the insulating strip 82 is provided with a cut away portion 87. The member 88 of conducting material and of the same area as the cut away portion 86 is designed to fit into the cut away portion and electrically connect the extreme right hand strips of units 72 and 73. It is to be understood that the conducting member 88 may be secured to these strips by brazing or some other suitable manner to provide a joint of low resistivity. Similarly the member 89 of conducting material is provided to fit into the cut away portion 87 and to electrically connect the left hand portions of units 73 and 74. This conductor member 89 is shown in position in Figure 3. By the use of the conductor members 88 and 89, the three units 72, 73, and 74 are connected in series so as to collectively provide six series connected thermocouples.

Referring to Figure 3, it will be noted that the thermopile unit 73 is somewhat longer than the unit 72 and that the unit 74 is in turn somewhat longer than the unit 73. The result is that the flame is able to contact a substantial portion of the hot junction of each of these units.

Application of burner structures

In Figure 5, as shown in schematic form, a burner control system utilizing the improved pilot burner of the present invention. A main gas burner is indicated by the reference numeral 92, this gas burner being supplied with gas by a pipe 93 from a mixing chamber 94. The mixing chamber is in turn connected through a pipe 95 with a motorized gas valve 96 which has a gas supply pipe 97 connected to the inlet side thereof. The motorized gas valve 96 is of any suitable type which remains open as long as it is energized and is closed by gravity or other suitable biasing means upon deenergization. The pilot burner 10 is secured to the main burner 92 by means of the stud 52. The burner head is connected to a gas supply pipe 98 which in turn is connected to the gas supply pipe 97 on the inlet side of valve 96. The thermopile 11 is connected by means of conductors 100 to an electromagnetically operated switch 101 of any suitable type designed to be operated by the current from a thermopile. For example, the switch may be of the type which is moved to closed position against a biasing means upon energization of

the electromagnet. On the other hand, the switch may be one which requires manually resetting of the switch. Such a switch is shown in the patent to Kronmiller No. 2,165,801 for "Switch" issued July 11, 1939.

The current for operation of valve 96 is supplied by a step down transformer 102 which has its primary side connected to line wires 103 and 104.

10 The energization of the valve 96 is controlled by a thermostat 105, this thermostat comprises a bimetallic element 106 to which is secured a contact arm 107. This contact arm is designed to engage with a fixed contact 108. A magnet 109 is positioned adjacent the contact arm 107 and is designed to cause the contact blade 107 to engage with and separate from contact 108 with a snap action. The bimetallic element 106 is so disposed that upon a temperature fall, the contact arm 107 is moved into engagement with contact 108.

15 Upon the temperature to which bimetallic element 106 is subjected falling to a predetermined value, the contact arm 107 is moved into engagement with contact 108. This results in the establishment of an energizing circuit to valve 96 as follows: from transformer 102 through conductor 110, contact 108, contact arm 107, bimetallic element 106, conductor 112, switch 101, conductor 113, valve 96 and conductor 114 back to the transformer 102. This circuit is established only if switch 101 is closed and switch 101 is closed only when current is supplied to the electromagnet thereof by the thermopile 11. Thus it is assured that the valve can never be energized and hence opened unless the thermopile 11 is heated by the pilot burner flame. If at any time the pilot burner flame is extinguished, the temperature of the hot and cold junctions of the thermopile will rapidly equalize to cause the thermopile to cease to generate current. The switch 101 will then move to open position and cause deenergization of the valve 96.

20 In the arrangement of Figure 5, the pilot burner was mounted vertically by means of the stud 52. In Figure 6, the pilot burner is shown as mounted horizontally through the flanges 36. It will be noted that the burner head 10 is fastened to a bracket 115 which in turn is secured to a burner 116. It will be noted that even though the burner is mounted horizontally the flame is still effective to both heat the hot junction of the thermopile 11 and also extend over the main burner so as to be capable of igniting the gas issuing from the same.

25 It will be seen that I have provided an extremely compact and highly effective assembly of a pilot burner and temperature responsive element. With this arrangement it is possible by the use of the relatively compact arrangement shown to generate a relatively large amount of power.

30 While I have shown a specific embodiment of the invention for purposes of illustration, it is to be understood that the invention is to be limited only by the scope of the appended claims.

I claim as my invention:

35 1. The combination comprising, a burner body having a relatively flat base portion, a burner head for said burner body enclosing an elongated passageway and providing an elongated orifice for controlling the flow of gas from the passageway of the burner head, means for connecting the passageway of the said burner head to fuel supply means, a relatively flat thermocouple hav-

ing a plurality of cold junctions secured to the relatively flat base portion of said burner body and the hot junctions thereof extending along and adjacent to the said elongated burner orifice.

2. In combination, a relatively flat burner head having a portion formed for connection with a fuel supply conduit and a passage extending from said portion through said burner head, said burner head being provided with an elongated slit communicating with said passage at the opposite end thereof from said connecting portion, and a flat thermocouple member secured to said burner head with its hot junction adjacent said slit, said thermocouple member comprising two flat relatively thin strips of materials of dissimilar thermoelectric characteristics, the lateral edges of which are joined at one end to provide the hot junction of the thermocouple, the width of said thermocouple adjacent said hot junction being substantially equal to the length of said slit.

3. In combination, a relatively flat burner head having a portion formed for connection with a fuel supply conduit and a passage extending from said portion through said burner head, said burner head being provided with an elongated slit communicating with said passage, and a plurality of flat thermoelectric current generating members secured to said burner head in spaced, superposed relation so that one end of each of said members is adjacent said slit and extends the full length thereof and so that the flame issuing from said slit successively contacts said ends.

4. In combination, a relatively flat burner head having a portion formed for connection with a fuel supply conduit and a passage extending from said portion longitudinally through said burner head, said head being provided with a groove extending perpendicularly to said longitudinal passage at the opposite end of said head from said connecting portion and forming with said longitudinal passage a T-shaped passage for the fuel, a closure member secured to said burner head over said groove, said closure having a slit therethrough substantially coextensive with said groove, and a flat temperature responsive element secured to said burner head with a portion thereof adjacent said slit and extending the full length of the slit.

5. In combination, a burner head of substantially rectangular cross section having a passage extending longitudinally therethrough and a flame opening communicating with said passage, a temperature responsive element secured to said burner head with a portion adjacent said opening, a slot formed in a side wall and forming two side flanges, one of said flanges having an open-

ing therethrough to accommodate fastening means for securing said burner head and temperature responsive element to a support, said slot being of a depth such as to provide only a relatively narrow separating wall between said slot and said passage, and said separating wall having an aperture therethrough to said passage to provide an air inlet for the burner.

6. In combination, a burner head, a burner jet extending into a recess in said head, said head having a passage extending from said recess longitudinally therethrough and a flame opening communicating with said passage, a temperature responsive element secured to said burner head with a portion adjacent said opening, a slot formed in a side wall and forming two side flanges, one of said flanges having an opening therethrough to accommodate fastening means for securing said burner head and temperature responsive element to a support, said slot being of a depth such as to provide only a relatively narrow separating wall between said slot and said recess, and said separating wall having an aperture therethrough to said recess at a point adjacent said jet to provide an air inlet for the burner.

7. In combination, a relatively flat burner head having a portion formed for connection with a fuel supply conduit and a passage extending from said portion through said burner head to a relatively long and narrow burner opening extending transversely of said burner head, a plurality of flat thermoelectric current generating members secured to said burner head in spaced superposed relation so that one end of each of said members is adjacent said burner opening, said ends being disposed in stepped relation with the end most remote from the opening projecting furtherest upward so that the flame issuing from said opening successively contacts said ends, and means for electrically connecting said members in series.

8. In combination, a burner head having a portion formed for connection with a fuel supply conduit and a passage extending from said portion through said burner head to a burner opening, a plurality of flat thermoelectric current generating members secured to said burner head in spaced superposed relation so that one end of each of said members is adjacent said burner opening and so that the flame issuing from said opening successively contacts said ends, and means for electrically connecting said members in series, each of said members comprising at least one pair of flat strips of materials of dissimilar thermoelectric characteristics, the lateral edges of which are joined at one end.

HUBERT T. SPARROW.
